Inventor.

J. O. HART

By Watson E. Coleman

Attorney

UNITED STATES PATENT OFFICE.

JACOB O. HART, OF LANCASTER, PENNSYLVANIA.

CARRIER.

1,238,909.

Specification of Letters Patent. Patented Sept. 4, 1917.

Application filed May 9, 1917. Serial No. 167,492.

To all whom it may concern:

Be it known that I, JACOB O. HART, a citizen of the United States, residing at Lancaster, in the county of Lancaster and State 5 of Pennsylvania, have invented certain new and useful Improvements in Carriers, of which the following is a specification, reference being had to the accompanying drawings.

10 This invention relates to certain improvements in carriers, and has relation more particularly to a device of this general character especially adapted for use in rural districts for transporting mail between a dwelling and highway; and it is an object of the invention to provide a novel and improved means whereby the operating means for the carrier proper may be employed in connection with an indicator, in order to show at 15 one end of the line of travel of the carrier when mail or the like has been deposited in the carrier at the opposite end of the line.

Furthermore it is an object of the invention to provide a device of this general character with novel and improved means whereby the operating means for the carrier proper is conveniently and effectively maintained in applied position and whereby the carrier proper is permitted to travel with 20 facility.

The invention consists in the details of construction and in the combination and arrangement of the several parts of my improved carrier whereby certain important 25 advantages are attained and the device is rendered simpler, less expensive and otherwise more convenient and advantageous for use, as will be hereinafter more fully set forth.

30 The novel features of the invention will hereinafter be definitely claimed.

In order that my invention may be the better understood, I will now proceed to describe the same with reference to the accompanying drawings; wherein—

Figure 1 is a view in side elevation illustrating a carrier transmission constructed in accordance with an embodiment of my invention;

50 Fig. 2 is a fragmentary view in elevation of one of the intermediate stationary supports;

Fig. 3 is a fragmentary view in top plan at the dwelling end of the apparatus;

Fig. 4 is an enlarged elevational view of 55 the clamp as herein provided; and

Fig. 5 is a view partly in end elevation and partly in section of the clamp as herein embodied.

As disclosed in the accompanying drawings, 1 denotes a stationary support adapted to be positioned adjacent a dwelling or the like, and 2 denotes a second stationary support adapted to be positioned adjacent the highway. Intermediate the supports 1 and 60 2 are additional stationary supports 3, of any number required by the necessities of practice. Rotatably supported by the support 1 and about a horizontal axis is a double sheave or pulley 4. The support 2 rotatably supports the single sheave or pulley 5 also mounted upon a horizontal axis.

C denotes the carrier proper, which is preferably cylindrical in form and having its opposite end portions conical. The upper wall of the carrier C is provided with a door 6, to facilitate the insertion or removal of mail or the like therein. The forward end portion of the carrier C is provided with a guideway 7, adapted to receive a slide 8. 75 The slide 8 is provided with suitable means to indicate to the mail man that the carrier C contains mail matter to be collected.

Secured to the opposite extremities of the carrier C are the flexible members F and M. 80 The member F is adapted to be wound around the sheave or pulley 4 within one of the grooves therein, and said member F is suitably anchored within said groove. The second member M is disposed around the 85 second pulley or sheave 5 and is then returned to the sheave or pulley 4 and adapted to be wound therearound in the second groove of the sheave or pulley 4. The member M is also suitably anchored within the 90 groove of the sheave or pulley 4. The return portion of the member M is engaged with the guide pulleys 9, suitably positioned upon the intermediate supports 3, whereby it is at once self-evident that the return portion of the member M is prevented from undue sagging, which otherwise would have a tendency to materially affect the successful 95 operation of the device.

When it is desired to cause the carrier C to 100 travel to the highway it is only necessary to impart the necessary rotation to the sheave or pulley 4, and as herein disclosed, said

pulley or sheave 4 is provided with an operating crank 10. However, I do not wish to be understood as limiting myself to this particular means of rotating the sheave or pulley 4, as any other means may be used which can be employed with convenience and facility.

In its travel toward the highway or toward the dwelling, the carrier C is adapted 10 to pass through the rigid loop members 11 extending upwardly from the tops of the intermediate supports 3, and through which upstanding loop members 11 the flexible members F and M are also adapted to travel. 15 It will be at once self-evident that by this means, the upper stretches of the members F and M, or those stretches of the members directly connected to the carrier C, are also prevented from sagging. To facilitate the 20 passage of the carrier C through the loop members 11, I find it of particular advantage to intersect the lower portion of said loop members with the anti-friction members 12, herein disclosed as rollers rotatably 25 mounted upon the upper ends of the supports 3 proper.

Suitably formed on the side face of the pulley or sheave 4 is an index 14, herein disclosed as in the simulation of an arrow; 30 and when said arrow is disposed upwardly and substantially vertical it gives indication that mail has been deposited within the carrier C at the highway. In assembling the device, the sheave or pulley 4 is so adjusted 35 as to cause the index 14 to be positioned beyond the vertical when the carrier C is at the limit of its movement relative to the highway. After the mail man has deposited matter within the carrier C it is only necessary for him to impart a slight outward movement to the lower stretch of the member M, to cause the index 14 to assume the desired vertical position. At this time it might be well to state that the index 14 is 40 preferably disposed radially of the sheave or pulley 4. The index 14 is also adapted to indicate when the mail carrier has left at the road side a parcel of a size too large to be deposited within the carrier C. In this 45 event, further pull is imparted to the lower stretch of the member M to cause the index 14 to point downwardly.

To facilitate the movement of the lower stretch of the member M, I find it of advantage to pivotally engage with the support 2, a lever 15 co-acting with a clamp 16 adapted to be detachably engaged with the lower stretch of the member M, whereby the requisite pull or pulls may be 50 imparted thereto for causing the partial rotation of the pulley or sheave 4 to bring the index 14 into one of its indicative positions. As this is particularly illustrated in Fig. 4, the clamp 16 comprises crossed members 17 pivotally connected one with the

other. Corresponding ends of the members 17 have pivotally engaged therewith, rigid links 18 which are also pivotally engaged with the rigid arm 19. The arm 19 is pivotally engaged with the lever 15, whereby the clamp 16 is caused to be moved in either direction. The end portion of one of the members 17, remote from the extremity thereof with which a link 18 co-acts, has pivotally engaged therewith a rigid 75 loop 20 through which the corresponding end portion of the second member 17 is loosely directed. The lower stretch of the member M is directed through the loop 20 and extends between the members 17. It 80 will be understood that when outward movement is imparted to the lever 15, the members 17 will clamp upon the lower stretch of the member M to effect the requisite pull thereon for controlling the position of the 85 index 14. Upon inward movement being imparted to the lever 15, the members 17 will separate so that the clamp 16 may be properly positioned upon the lower stretch of the member M to effect a second pull. 90 By having the member M disposed through the loop 20, the clamp 16 is at all times maintained in operative position relative to the member M. It will also be understood that the loop 20 permits an unobstructed 95 travel of the lower stretch of the member M therethrough so that no hindrance or obstruction will be offered to the movement of the carrier C in either direction.

I have also found it of advantage to provide at the road end of my device, a buffer or stop for limiting the movement of the carrier toward the road. As herein embodied, the buffer or stop comprises a flat spring 21 secured to the upper end portion 105 of the post 2, and disposed inwardly on such inclination as to intersect the travel of the upper stretch of the member 1 and terminating a slight distance inwardly of the sheave or pulley 5. As herein embodied, the upper 110 stretch of the member M is loosely disposed through the free extremity of the spring 21.

From the foregoing description, it is thought to be obvious that a carrier constructed in accordance with my invention 115 is of an extremely simple and comparatively inexpensive nature and is particularly well adapted for use by reason of the convenience and facility with which it may be assembled; and it will also be obvious 120 that my invention is susceptible of some change and modification without material departure from the principles and spirit thereof, and for this reason I do not wish to be understood as limiting myself to the 125 precise arrangement and formation of the several parts herein shown in carrying out my invention in practice, except as herein-after claimed.

Having thus fully described my invention, 130

what I desire to claim and secure by Letters-Patent, is:

1. A device of the character described comprising a plurality of spaced supports, 5 sheaves rotatably mounted upon said supports, a carrier, flexible means co-acting with the opposite ends of said carrier and co-acting with the sheaves whereby rotation of one of the sheaves will impart movement 10 to the carrier, and an indicating means carried by one of the sheaves.
2. A device of the character described comprising a plurality of spaced supports, 15 sheaves rotatably mounted upon said supports, a carrier, flexible means co-acting with the opposite ends of said carrier and co-acting with the sheaves whereby rotation of one of the sheaves will impart movement 20 to the carrier, an indicating means carried by one of the sheaves, and additional means engageable with the flexible means for imparting limited movement to the sheave provided by the indicating means.
3. A device of the character described, 25 comprising a plurality of spaced supports, sheaves rotatably mounted upon certain of said supports, the intermediate supports being provided with guides, a carrier, flexible members secured to opposite ends 30 of said carrier and co-acting with the sheaves whereby rotation of one of the sheaves will impart movement to the carrier; said flexible members being also disposed through the guides of the intermediate supports; and an indicating means carried by 35 one of the sheaves.
4. A device of the character described,

comprising a plurality of spaced supports, sheaves rotatably mounted upon certain of said supports, the intermediate supports 40 being provided with guides, a carrier, flexible members secured to opposite ends of said carrier and co-acting with the sheaves whereby rotation of one of the sheaves will impart movement to the carrier, said flexible 45 members being also disposed through the guides of the intermediate supports, an indicating means carried by one of the sheaves, and additional means for imparting limited movement to the sheave provided 50 with the indicating means.

5. A device of the character described, comprising a plurality of spaced supports, sheaves rotatably mounted upon certain of said supports, the intermediate supports 55 being provided with guides, a carrier, flexible members secured to opposite ends of said carrier and co-acting with the sheaves whereby rotation of one of the sheaves will impart movement to the carrier, said flexible members being also disposed through the guides of the intermediate supports, and a flat spring carried by one of the supports and intersecting the line 60 of travel of a flexible member and through which said member is loosely disposed, said spring serving to limit the movement of the carrier in one direction.

In testimony whereof I hereunto affix my signature in the presence of two witnesses.

JACOB O. HART.
